**TWO-STAGE ADJUSTABLE GAS PRESSURE
REGULATOR**

George L. Hammon, Oakland, Calif.

Application May 10, 1956, Serial No. 41,436

Term of patent 14 years

(Cl. D52—1)

FIG. 1.

FIG. 2.

FIG. 3.

FIG. 4.

FIG. 5.

Fig. 1 is a perspective view of a two-stage adjustable gas pressure regulator, illustrating my new design;

Fig. 2 is a left side view of the same regulator;

Fig. 3 is a right side view of the same regulator;

Fig. 4 is a front view of the same regulator; and

Fig. 5 is a rear view of the same regulator.

The parts of the regulator shown in broken lines are for illustrative purposes only.

I claim:

The ornamental design for a two-stage adjustable gas pressure regulator, as shown and described.
